UNITED STATES PATENT OFFICE.

LEWIS H. McCULLOUGH, OF RICHMOND, INDIANA.

NON-INTERFERING FIRE-ALARM TELEGRAPH SYSTEM.

SPECIFICATION forming part of Letters Patent No. 329,187, dated October 27, 1885.

Application filed April 1, 1885. Serial No. 160,936. (No model.)

To all whom it may concern:

Be it known that I, LEWIS H. McCULLOUGH, a citizen of the United States, residing at Richmond, in the county of Wayne and State 5 of Indiana, have invented certain new and useful Improvements in Non-Interfering Fire-Alarm Telegraph Systems; and I do hereby declare the following to be a full, clear, and exact description of the invention, such as 10 to will enable others skilled in the art to which it appertains to make and use the same.

My present invention is an improvement on that shown and described in an application still pending in the United States Patent Office, and entitled a "non-interfering fire-alarm telegraph system," and it relates, chiefly, to an arrangement of circuits and apparatus whereby the amount of wire to be used in my system is greatly reduced. In the invention 15 above referred to I connect all the signal-boxes in a city system with a single central-office apparatus which is located in one of the engine-houses. This arrangement necessitates the running of a large number of wires, some 20 of them over long distances, to the central office. In the arrangement to which my present invention relates I locate similar apparatus in every engine-house, or in as many as desirable or convenient, and run to the central office only a single wire from each engine-house. In this way every box is connected 25 with an indicating apparatus which is near at hand, instead of requiring to be joined by a conductor of great length to the central office. 30 My improved system is illustrated in the accompanying drawing, which forms a part of this specification. The indicating apparatus at all the engine-houses, including that which forms the central office, is the same in 35 general construction, but for convenience I have illustrated in detail the central-office apparatus near the center of the drawing.

Referring to the drawing as a whole, A A are dials having around their edges numerals, 40 as 7, 9, 13, &c., representing the numbers of fire-alarm signal-boxes. The dials in different engine-houses will of course be differently numbered, as they will be connected with entirely distinct sets of signal-boxes. Opposite 45 each numeral is an oblong slot, a, whose longitudinal diameter is substantially at right

angles to that radius of the dial which passes through the center of the slot.

A hand or pointer, B, which normally tends to move in the direction of the arrow, under the influence of a spring, (not shown,) is mounted on a driving-shaft and held from turning by the stop d, as shown. The stop d is attached to an armature pivoted behind the dial, and is held out so as to engage with the 60 pointer B by a spring in the usual manner. The armature is operated by the electro-magnet E, attached to the frame of the dial.

In the same circuit with the electro-magnet E is a second electro-magnet, F, which is attached to the front part of the dial-box. Its armature-lever H is pivoted at g, and has no retractile spring, but is kept in any position in which it is placed (normally away from the core of the magnet F) by the force of the 65 spring h, pressing the extension k of the armature lever H against one end of the slot a in the dial-face. The extension k is loosely pivoted to the armature-lever H, and is located substantially at right angles to the armature-lever. In pressing the extension k against one end of the slot a, the spring h also presses it against the platinum point n on the conducting-arm m, attached to the dial-box. The driving-shaft is connected through the 70 engine-houses Y or bell-towers, or both, to one pole of the battery W. The other pole is connected through the signal-boxes with the extensions k. The circuit within the 75 box is from extension k to the platinum point n and the arm m; by wire 5 to the electro-magnet F; by wire 6 through a common point, r, to electro-magnet E; by wire 7 to stop d, to pointer B and driving-shaft.

There are as many extensions k and magnets F for operating the indicator of any given engine-house as there are signal-boxes in the system connected with that engine-house, and the number of signal-boxes will usually correspond to the number of slots in the dial, less 85 one, although the dial may be constructed to have several more slots than there are signal-boxes, to provide for future needs or contingencies.

The magnet E, which actuates the stop d, is 90 common to all the circuits, the wire from every magnet F being connected to the wire 6, which

runs to the magnet E at some convenient point, as *r*.

The actuating spring for the hand B is made stronger than the spring *h*, for a reason that 5 will be presently explained.

Every signal-box is connected with one of the extensions *k* in some one of the different engine-houses.

The above description applies to the indicating apparatus in every engine-house, except so far as it implies that the return-circuits pass directly from the indicator-hands through gong and bell magnets back to the battery. Instead of doing that, they pass to 15 the extension *k* on the indicating apparatus at the central station, the circuit going from the hand of that indicator directly to the gongs and bells.

The operation of the apparatus in any given 20 engine-house is as follows: On the ringing in of an alarm from any box—say 24—the magnet F connected with that box is operated, and also the magnet E, which is common to all the box-circuits. This causes the stop *d* to 25 be removed from the path of the hand B, and also causes the end of the extension *k* to be pushed out into that path. The hand B, on being released, travels in the direction of the arrow until it strikes against the end of the 30 extension *k*, which, in obedience to the superior power of the driving-spring, moves to the opposite end of the slot *a*, thereby breaking the circuit of magnets F and E at *n*, and cutting out of the circuit all magnets except the 35 gong and bell magnets. The circuit is now from one pole of the battery, through the signal-box 24, to the extension *k*, connected with that box, to the hand B, and from there to the hand of the central-office apparatus by an ex- 40 actly similar course—namely, through the extension *k* to the hands. From this point the circuit passes to the battery through the gong and bell magnets. The first stroke of 24 is made on the gongs and bells, when the circuit 45 is first completed, through the magnets F and E. The remaining strokes are made after those magnets have been cut out.

In point of fact, the circuit will probably run from the hand of the indicator in every 50 engine-house directly to the gong-magnet in that house, and will afterward pass to the indicator at the central office. For convenience of illustration, however, I have shown the apparatus as above described. The bell-towers 55 will usually be located in a circuit between the central-office indicator and the battery.

The extensions *k* will be held in their forward position by the force of the spring *h* pushing against the end of the pointer B. 60 After a signal has been sent in, the extension *k* will be restored by hand, or by automatic mechanism such as I describe in an application for Letters Patent filed on the 15th day of January, 1885.

65 It will be observed that both the original and the secondary circuits pass through the

pointer B. As soon, therefore, as the pointer B has left the stop *d*, there is no circuit for any box except one that has already been operated. Moreover, in case two boxes should be operated at the same time, the pointer B would be mechanically obstructed from passing to the extension *k* which was farthest around the dial until the nearest extension *k* had been pushed back after the receipt of the box-signal. The magnets F and E being operated simultaneously, the end of the extension *k* will always be out in position to engage the pointer B as soon as it comes along.

The numerals in the central-office apparatus, 70 instead of indicating the numbers of signal-boxes, will represent the numbers of the precincts or engine-houses from which the alarms come. It is clear that just as it is impossible that the signals from two boxes should interfere, so no interference can take place at the central office between the signals from two or more precincts.

The central office or station will usually be located in one of the engine-houses. The signal-boxes connected with any given engine-house may be called a "system" of signal-boxes.

It will be observed that the system of signal-boxes represented at the bottom of the drawing is joined to a different loop, X', running from the same pole as the loop X. The number of loops may be as great as is found convenient.

Having now described my invention, what I 80 claim, and desire to secure by Letters Patent, is—

1. The combination, with an electric-circuit conductor running in a loop from one pole of a generator back to the same pole, of two or more systems of circuit-closers connected with different engine-houses in multiple-arc relation between the said conductor and the opposite pole of the generator, electro-magnetic apparatus at every engine-house, adapted to be actuated by the operation of any circuit-closer, whereby every other circuit-closer is cut out of the circuit, similar apparatus at a central station for cutting out all the systems except one in which a circuit-closer is first operated, and suitable receiving apparatus for receiving the signal on the operation of any circuit-closer, substantially as set forth.

2. The combination, with an electric-circuit conductor running in a loop from one pole of a battery back to the same pole, of two or more systems of signal-boxes connected with different engine-houses in multiple-arc relation between the said conductor and the opposite pole of the battery, electro-magnetic apparatus at every engine-house, adapted to be actuated by the operation of any signal-box, whereby the particular signal-box is indicated and every other box is cut out of the circuit, similar apparatus at a central station for indicating the particular system and cutting out all the rest, and suitable gong and bell magnets.

for receiving the box-signals, substantially as set forth.

3. An electric-circuit conductor running in a loop from one pole of a battery back to the same pole, two or more systems of circuit-closers, each connected to a hand in the engine-house belonging to its system, and electro-magnetic apparatus at every engine-house, adapted to be actuated by the operation of any circuit-closer to release the hand and form a new circuit to the exclusion of the rest of the circuit-closers, in combination with conductors running from the different hands through similar apparatus to a hand at a central station, the latter hand being connected through a suitable receiving apparatus to the pole of the battery opposite that to which the loop is connected, substantially as set forth.

4. The combination, with two or more electric-circuit conductors, each running in a loop from the same pole of the same battery back

to the pole from which it started, of two or more systems of circuit-closers connected with different engine-houses in multiple-arc relation between the said conductors and the opposite pole of the battery, electro-magnetic releasing apparatus at every engine-house, adapted to be actuated by the operation of any circuit-closer to cut every other circuit-closer out of the circuit, similar apparatus at a central station for cutting out all the systems except one in which a circuit-closer is first operated, and suitable receiving apparatus for receiving the signal on the operation of any circuit-closer, substantially as set forth.

In testimony whereof I have affixed my signature in presence of two witnesses.

LEWIS H. McCULLOUGH.
